No. 15,643

DEC 23, 1884

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,643, dated December 23, 1884.

Application filed November 15, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,516;) and I do hereby declare that the engraved prints accompanying this specification convey to any one accustomed to using paper patterns a clear understanding of how 5 to a garment made up by the pattern will appear.

The design shows a round walking skirt and a basque. The skirt exhibits a plain right-front drapery falling almost to the lower edge, 15 a short-pointed left-front drapery disclosing draping plaits in its front and back edges, and appearing to be overlapped at its front edge by the upper part of the right-front drapery, a deep full back drapery that exhibits draping 20 plaits high up in its front edges, loopings

at the center, and a revers below the plaits in the left side. The basque exhibits closely-fitted vest-fronts flaring in a point at each side of the closing, deeper closely-fitted jacket-fronts that appear to be cut away with a broad 25 flare above and below the bust, a closely-fitted back that displays under-folded plaits at the lower end of its middle seam, a standing collar, a deep collar extending in broad lapels to the bust, and coat-sleeves.

What I claim as my invention, and desire to 30 secure by Letters Patent, is—

The design for a lady's costume, as shown in the engraved prints accompanying this specification.

SARAH JANE SHIELS.
